US0D1063800S

(12) **United States Design Patent** (10) **Patent No.:** **US D1,063,800 S**
(45) **Date of Patent:** ** *Feb. 25, 2025

(54) **CENTER TUNNEL CONSOLE**

(71) Applicant: **VOLVO CAR CORPORATION**, Gothenburg (SE)

(72) Inventor: **Patrik Müller**, Gothenburg (SE)

(73) Assignee: **Volvo Car Corporation**, Gothenburg (SE)

(*) Notice: This patent is subject to a terminal disclaimer.

(**) Term: **15 Years**

(21) Appl. No.: **29/893,388**

(22) Filed: **May 30, 2023**

(30) **Foreign Application Priority Data**

Nov. 30, 2022 (EM) 015004835-0003

(57) **CLAIM**

The ornamental design for a center tunnel console as shown and described.

DESCRIPTION

FIG. 1 is a front perspective view of the center tunnel console showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a rear perspective view thereof.

1 Claim, 8 Drawing Sheets
